UNITED STATES PATENT OFFICE

FRANK E. LEWIS, OF EAST PITTSBURGH, PENNSYLVANIA, ASSIGNOR TO WESTINGHOUSE ELECTRIC & MANUFACTURING COMPANY, A CORPORATION OF PENNSYLVANIA

EXPRESS-LOCAL ELEVATOR CONTROL SYSTEM

Application filed June 10, 1927. Serial No. 197,830.

My invention relates to control systems for motors and has particular reference to systems of control for hoists, elevators, vehicles and similar apparatus.

5 An object of my invention is to provide a control system for vehicles traveling over a predetermined path, wherein the vehicle may be caused to operate at one speed over a portion of the path and at a different speed 10 over another portion of the path.

Another object of my invention is to provide a control system for so-called express elevators wherein the elevator will be caused to travel at a normal speed over that portion 15 of its path known as the local zone and at an increased speed over that portion known as the express zone.

Another object of my invention is to provide a control system for express and local 20 elevators wherein the speeds in the several zones may be automatically controlled without the necessity of the attendant or operator on the car giving attention to the position of the car relative to zones.

25 My invention will be described in combination with the accompanying drawings wherein,

Figure 1 is a diagrammatic view of a bank of elevators serving a plurality of floors, 14 30 in number, and showing the relative positioning of the express and local zones.

Fig. 2 is a diagrammatic view of the control system for an elevator embodying my speed-control system.

35 In Fig. 1 is shown three elevator hatchways indicated as A, B and C, in each of which an elevator car indicated as A', B' and C', respectively, operate in the usual manner. The cars are respectively suspended by means of 40 cables extending from them over hoisting drums A'', B'' and C'', respectively, to counter-weights A''', B'''' and C''''. In each of the hatchways, a pair of inductor irons are positioned, these inductor irons defining 45 the point between the local and the express zones. For example, in the hatchway A, an inductor iron 15 is indicated as positioned slightly above the third-floor level and on the left-hand side of the hatchway. A similar 50 inductor iron 16 is shown as slightly below

the fourth-floor level upon the right-hand side of the shaft. With this arrangement, we may assume that the elevator A is to operate to give express service, that is, to stop at none of the floors between the first 55 and the fourth floors and thereafter to proceed, as a local elevator, from the 4th to the 14th floors, that is, the car will make all necessary stops between the 4th and the 14th floors in response to the usual passenger-operated signal devices ordinarily provided in elevator-control systems. By a similar arrangement of inductor irons 17 and 18, the elevator B may be operated as an express elevator to the 9th floor and operate as a local 60 elevator for the remaining floors, while elevator car C may give local service to the first eight floors and express service from the ninth floor to the upper terminal.

This express and local operation is usual 70 in very tall buildings in order to prevent the traffic to or from a given section of the building from crowding the traffic to or from a different section of the building. As may readily be seen, should the elevator A, for 75 example, start from the first floor and make all of the stops at floors between the first and 14th, the capacity of the elevator would have to be very great in order to provide room on the car to take on the passengers 80 at the 12th or 13th floors. Similarly, on a down trip, the condition of stopping at all of the floors would cause the car to be so crowded as it approaches the few lower floors that there would be no room for additional passengers from these floors to be cared for by this car. This local and express system of operating elevators is quite usual 85 in present-day buildings of more than ten stories in height.

90 My system for controlling elevators during their passage through the express and local zones comprises a means for operating the elevator at an express speed while passing through the express zone and then reducing the speed to the working speed for the car, as the car passes into the local zone.

95 Fig. 2 illustrates the control system embodying my invention and comprises an elevator car C suspended by means of a cable 100

CA which passes over a hoisting drum D to a suitable counter-weight CW. The hoisting drum D may be driven in any suitable manner, and, in the illustrated embodiment of my invention, the driving means comprises a motor-generator-motor-set of the Ward-Leonard type. This set comprises a driving motor M, provided with a shunt field winding MF and having its armature M' directly coupled to the armature G' of a generator G. The generator G is of the compound-wound type and comprises an armature G', a series field winding GSF, a shunt field winding GF, and a demagnetizing field winding GAF. The armature G' of the generator G is connected in "loop" circuit with the armature EM' of an elevator hoisting motor EM. The elevator motor EM is provided with a shunt field winding EMF, and has its armature EM' directly coupled to the hoisting drum D. The direction and speed of the hoisting motor EM is controlled in any suitable manner, as by controlling the direction and amount of current through the shunt field winding GF of the generator G. This control is illustrated as comprising an "up" direction switch 1, and a "down" direction switch 2 for alternately connecting the generator shunt field winding GF to line conductors L₁ and L₂, with the current passing in opposite directions. The speed of the motor EM is varied by the inclusion or exclusion of a resistor R, selectively controlled by a speed relay 3.

The various direction and speed relays may be controlled from the elevator car C by means of a car switch CS and a series of slow-down and stop inductor relays 6, 8, 10 and 12.

The control system may be briefly described as follows:

Assuming that it is desired to move the car upwardly, the car switch CS is moved about its pivot CS', toward the right, energizing the "up" direction switch 1 by way of a circuit which extends from line conductor L₁, through conductors 30, 31, the coil of "up" direction switch 1, conductor 32, through the usual flexible cable indicated, by the arrow heads on the several conductors illustrated, to contact member 33 of the car switch CS, thence through the segmental contact 34 of the car switch CS, through conductors 35 and 36, to line conductor L₂.

The closing of the "up" direction switch 1 completes a circuit for the generator shunt field winding GF which extends from line conductor L₁, through conductors 30, 31 and 37, contact members 1a, conductor 38, resistor R, conductor 39, field winding GF, conductor 40, resistor R', conductors 41 and 42, contact members 1b, conductor 43, conductor 44, and conductor 36 to line conductor L₂. This energization of the generator

shunt field winding GF causes the generator G to supply the hoisting motor EM with voltage in one direction and the car starts upwardly. A holding circuit for the "up" direction switch 1 is completed by way of a circuit which extends from line conductor L₁, through conductors 30 and 31, the coil of "up" direction switch 1, conductor 32, conductor 45, contact members 1d, conductor 46, conductor 47, and in series through the normally closed contact members of the stopping inductor relays 8 and 12, thence by way of conductors 48 and 36, to line conductor L₂. In this manner, the elevator car once started continues to operate until the stop inductor relay 8 is moved to the dotted-line position, thus opening its contact members and de-energizing the previously traced holding circuit for the "up" direction switch 1. Further movement of the car switch causes a circuit to be completed for the speed relay 3 which extends from line conductor L₁, through conductors 30 and 51, the coil of relay 3, conductors 52 and 53, to contact member 54 of the car switch CS, and thence, by way of the segment 34 and conductors 35 and 36 to line conductor L₂. This operation of the relay 3 shunts the resistor R from the generator shunt field circuit by way of contact members 3a, conductors 55 and 56, thus causing the motor to operate at high speed. This speed which is hereinafter referred to as the high speed is intended to be the highest working speed which the elevator will attain while in a local zone.

The speed relay 3 completes a self-holding circuit which extends from line conductor L₁, through the conductors 30 and 51, the coil of relay 3, conductor 52, conductor 57, contact members 3b, conductor 58, and thence, in series, through the normally closed contact members of slow-down inductor relays 6 and 10, by way of conductor 59, thence, by way of conductor 36, to line conductor L₂.

It is, therefore, seen that the motor will be maintained in operation at its high speed until the slow-down inductor relay 6 has been operated, as described for the relay 8. The relay 6 cooperates with a magnetizable inductor plate 7, one of which is mounted adjacent each of the floors at which the elevator is to stop. The coils of the inductor relays 6, 8, 10 and 12 are energized only when the car switch has been moved to neutral position, since the circuit for these coils leads through to central contact 60 on the car switch CS.

All of the foregoing description of the control system for the elevator is disclosed in the copending application of E. M. Bouton, Serial No. 731,921, filed August 14, 1924, and assigned to the Westinghouse Electric & Manufacturing Company, and I claim no part of this system as my invention.

In series with the generator shunt field winding GF, I have illustrated a resistor R'

which may be excluded from this circuit by the operation of a relay 24. The function of this resistor is to maintain the speed of the motor at the high-speed operation mentioned previously, and it is my purpose to exclude this resistor when the car passes into the express-speed zone, thereupon causing the motor to operate at an abnormal speed or a speed above the usual high working speed.

10 For example, the normal working speed of the elevator may be 600 feet per minute and the express or abnormal speed may be considerably in excess of 600 feet per minute, for example, 750 to 900 feet per minute.

15 These speeds are merely illustrative, and the express speed may be given any value within well-known safety limits. The relay 24 is energized through the agency of a pair of inductor relays 20 and 22, indicated by similar reference numerals in Fig. 1, in the manner hereinafter described. A relay 25 is provided, having its contact members 25a in

20 series with the coil of relay 24.

The operation of relays 20, 22, 24 and 25 may be best described with reference to an assumed operation. Assume the conditions of operation described for the elevator car A' with reference to Fig. 1, the elevator may be started from the first floor by a movement of the car switch CS and the consequent operation of the control system previously described, the car will move upwardly on its first trip at high working speed. When the car arrives at the 14th floor

25 and is reversed for the down trip, the movement of the car switch CS to the left closes a circuit for the relay 22 which extends from line conductors L₁, through conductors 30, 31, 61 and 62, contact members 2a, conductors 63 and 64, one of the sets of contact members of a double-pole switch 26 on the car, conductor 65, the coil of inductor relay 22, and conductors 66 and 36, to line conductor L₂. Until the inductor relay 22 passes

40 the "down" inductor iron 16, in this case slightly below the 4th floor level, the inductor relay 22 is ineffective to control any operation of the motor. The car will, therefore, proceed as a local elevator, that is, at

45 the normal working speed from the 14th to the 4th floors, making the necessary stops in response to passenger-operated signals. As the car leaves the 4th floor, the relay 22 passes the inductor iron 16, and the relay is actuated

50 to close its contact members 67, thus completing a circuit which extends from line conductor L₁, through conductor 68, the coil of relay 25, conductor 69, the contact members 70 of the relay 20, conductors 71 and 72, the contact members 67 of the relay 22, conductors 73, 66 and 36 to line conductor L₂.

The relay 25 closes its contact members 25a, completing a circuit to energize the relay 24, which circuit extends from line conductor

55 L₁, through conductors 74, contact members

25a, conductor 75, the coil of relay 24, and conductor 76 to line conductor L₂. This energizes relay 24 and excludes the resistor R' from the generator field circuit, as previously described, and the car proceeds to the 70 first floor at the abnormal or express speed. Suitable limit switches are provided to cause the car to stop at the first floor. Since these limit switches are universally provided in elevator systems, to stop the car at its limits 75 of travel, it has not been deemed necessary to illustrate them here.

The relay 25 closes a self-holding circuit which extends from line conductor L₁, conductor 68, coil of relay 25, conductor 69, contact members 70 of the relay 20, conductors 71 and 77, contact members 25c and conductor 78 to line conductor L₂.

When the car is again started upwardly, the relay 25 remains energized, since the 85 only point at which the circuit for this relay may be broken is at the normally closed contact members 70 of the inductor relay 20, and the car moves at express speed until it arrives at the third floor. As the car passes 90 the third floor, the inductor iron 15, cooperating with the relay 20, causes this relay to open its contact members 70 and thus de-energizes the relay 25 and, consequently, 95 the relay 24.

The coil of the relay 20 is energized at all times during which the relay 25 remains closed, and the "up" direction switch 1 is energized. The circuit for this coil extends from line conductor L₁, through conductors 100 30, 31, 61 and 79, contact members 1e, conductor 80, contact members 25b, conductor 81 to the other set of contact members of the double-pole switch 26 on the car, conductor 82, the coil of relay 20, and conductors 105 83, 66, and 36 to line conductor L₂.

The operation of the relay 20, therefore, deenergizes relay 25 and opens the circuit excluding resistor R', and the car operates from the 4th to the 14th floors at its local 110 speed.

It is thus seen that, with my system, the car will operate through a predetermined zone or past a predetermined number of floors at a very high speed and at a slower speed 115 through the remaining zone or past the remaining floors. This slower speed is limited by the highest economical and practical speed, with which local stops may be made. The use of my system, therefore, renders it possible to substantially reduce the time necessary for an express-local elevator to complete a round trip, by operating through the express zone at a speed which would be 120 prohibitive in its working or local zone.

The double-pole switch 26 shown on the car, may be opened at will, thus disconnecting the automatic express-local feature and permit the elevator to operate at its normal 125

working speed throughout its entire path of travel.

The apparatus disclosed is merely illustrative, and I do not desire to be limited to the details shown, except as defined in the appended claims.

I claim as my invention:

1. In a control system for elevators, an elevator car operable over a predetermined path between a plurality of floors, elevator motive means operable at different speeds, a switch, a coil normally ineffective to actuate said switch, both switch and coil being carried by said car, means defining zones of operation for said car in said path, said means comprising magnetizable plates mounted at the boundaries of said zones for magnetically rendering said coil effective to actuate said switch when said car passes the boundary of any of said zones, and speed control means for said motive means operably responsive to actuation of said switch for determining the speed of operation of said car within the approached zone.
2. In a control system for elevators, an elevator car operable over a predetermined path between a plurality of floors, elevator motive means comprising a motor-generator-motor operable at different speeds, means for controlling said generator to operate said elevator at a normal high speed or at a speed above said normal speed selectively, a switch, a coil normally ineffective to actuate said switch, both switch and coil being carried by said car, means defining zones of operation for said car in said path, said means comprising magnetizable plates mounted at the boundaries of said zones for magnetically rendering said coil effective to actuate said switch when said car passes the boundary of any of said zones, and speed-control means for said motive means operably responsive to actuation of said switch for determining the speed of operation of said car within the approached zone.
3. In an elevator-control system, an elevator operable past a plurality of adjacent floors, motive means for said elevator, express-speed control means for said motive means, a plurality of switches mounted on said car, each of said switches comprising a coil normally ineffective to actuate the associated switch, an actuating circuit for said express-speed control means comprising a common portion controlled by one of said switches, and having a plurality of branches, one of said branches being under the control of another of said switches, means defining an express zone of operation for said elevator, said means comprising magnetizable members mounted in the hatchway at the boundaries of said zone for magnetically rendering said coils effective to actuate the associated switches, one of said means being disposed to render the switch controlling said

branch effective to actuate said express-speed control means upon entrance of said elevator in said express zone, and another of said means being disposed to render said switch controlling said common portion of said circuit effective to render said express-speed control means ineffective upon exit of said elevator from said express zone, and means rendered effective upon actuation of said express-speed control means to complete a maintaining circuit therefor through another of said branches.

4. In a control system for an elevator car operable in a hatchway through express-speed and local-speed zones, motive means for moving said elevator, switching mechanism actuatable to cause said motive means to operate at a predetermined speed, additional switching mechanism for causing said motive means to operate at an express speed, and means to automatically control said additional switching mechanism when said car approaches the junction of said zones to thereby determine the speed of the car in the approached zone, said means comprising a switch having two relatively movable elements, one of said elements including a circuit controlling armature and a coil, and the other of said elements including a magnetizable plate adapted to cooperate with said coil to actuate said armature when said two elements are adjacent each other, means for mounting one of said elements on said car, and means for mounting the other of said elements in said hatchway.

In testimony whereof, I have hereunto subscribed my name this 27th day of May, 1927.
